UNITED STATES PATENT OFFICE

JOHN A. KATZ, OF YORK, PENNSYLVANIA, ASSIGNOR TO S. FORRY LAUCKS, OF YORK, PENNSYLVANIA

LOCK FOR SAFE-DEPOSIT BOXES

Application filed October 14, 1926. Serial No. 141,564.

This invention relates to a lock and is primarily adapted for use in connection with safe deposit boxes or elsewhere where a master key is held by an establishment and an individual key is held by the customer, although no limitation as to this use is to be inferred.

It is primarily aimed to provide a novel construction wherein the combination necessary to operate the lock on the part of the individual or customer may be readily changed, as is advisable when a safe deposit box is transferred from one customer to another, a key becomes lost or otherwise.

Another object is to provide a novel construction wherein a unit is provided containing the permutation disks and which unit is removable so that another may be applied in its stead, to thereby vary the combination with respect to the customer's or individual's key.

Still other objects are to provide a novel construction of locking arms to hold the units in place, which arms are displaceable by a key and which key also controls the displacement of adjacent lock parts so as to provide due clearance for the removal of the unit, and also to provide a structure having a rigid casing for the unit and the latter of such form that it cannot be incorrectly inserted.

Various additional objects and advantages will become apparent from a consideration of the description following taken in connection with accompanying drawings illustrating an operative embodiment.

In said drawings:—

Figure 1 is a front view of the lock, with the front plate removed to disclose details;

Figure 2 is a rear view of the lock;

Figure 3 is a sectional view taken on the line 3—3 of Figure 1;

Figure 4 is a sectional view taken on the line 4—4 of Figure 3;

Figure 5 is a detail perspective view of my novel unit;

Figure 6 is an end elevation of the lock;

Figure 7 is a front view of the cover or facing plate of the lock;

Figure 8 is a sectional view taken on the line 8—8 of Figure 7,

Figures 9 and 10 are transverse sectional views of the lock unit, and

Figure 11 is a longitudinal sectional view of the lock unit showing the spindle in elevation.

Referring specifically to the drawings, the lock comprises a rectangular casing as at 10, formed with integral side and end walls, and initially open at one side but closed at such side by a facing plate as at 11, which may rest on lugs 12 of the section 10 and which may be secured in place by a screw or the like passed through an opening 13 in plate 11 and engaging an interiorly screw threaded stud 14 of section 10.

Fixed adjacent one end within the section 10 is a stud 15 on which the locking bolt 16 slides, by reason of the provision of an elongated slot 17 in the latter engaging said stud. The bolt passes through a rectangular opening at 18 in one end of casing 10. The sliding movement of said bolt 16 is limited by a pin 20 on section 10.

Projecting laterally from the bolt 16 is a detent lug 21 coacting with which are a series of arms 22 in the form of individual levers pivoted on the stud 15 and each having a spring 23, carried thereby and engaging a part of the casing 10, thereby urging the levers toward the detent 21, so that projection 24 on such detent will abut such detent 21. The detent 21 and projection 24 prevent retraction of the bolt only when the removable unit is operated first and it is therefore a safeguard only against the front unit. Retraction of the bolt is also prevented by small block 16^a fastened to the upper side of the case 10. The arms 22 have slots at 25. The slots 25 are at different locations so that they will be staggered when the projections 24 engage the lug 21. Key means is provided however, whereby the arms 22 may be actuated to aline the slots 25 and also aline them with respect to the detent 21 so that the bolt 16 may be operated for retraction, the slots 25 in that event receiving the detent 21.

Such key controlled means may comprise a spindle as at 26 provided with a key slot 27 therethrough. One end of the spindle 27 is reduced as at 28 and journaled removably in

an opening 29 in the casing 10. It will be understood that an appropriate key is adapted for insertion through the slot 27, having bits of different lengths, so as to depress the arm 22 to the different extents necessary for alinement of the slots 25, to receive the detent 21.

Pivoted to the locking bolt 16 as at 30, is a latch 31 having a lug 32 at one end thereof. A coil spring 33 surrounds the pivot 30, engaging the latch 31 at one end and to the bolt 16 at the other end, whereby the latch 31 is urged at the lug 32 toward or into engagement with suitable permutation disks 34. Operation of disks 34 is key-controlled, being adapted for operation by a customer's or individual's key while the arms 22 are adapted for operation by a master key such as is used in a safe deposit room of a bank for various locks, to unlock them prior to further unlocking by the customer. The disks 34 have slots 35, when alined, adapted to receive the free end of lug 32.

Said block 16^a acts against lug 32 of latch 31 until the lug 32 drops into the slots of the disks, this position of the disks being only obtained by the proper key alining the slots of the disks and therefore operating the lock.

The said disks 34 form parts of the permutation key unit heretofore referred to and specifically shown alone in Figure 5. This unit comprises a holder 35^a having a disk end 36 preferably knurled peripherally at 37 so that it may be more readily gripped. The side walls of the holder 35^a are arcuate and adjacent the disk 36 have grooves as at 38. One end of the holder has a plate at 39 permanently fastened or removable as preferred and held in place as on pins 40 extending from the holder 35^a. Journaled removably in the disk end of the holder is a spindle 41 which is also journaled in the plate 39, projects beyond the same and has a key insert groove as at 42, whereby a key may be inserted through the same to engage the disks 34 to lock or unlock the bolt 16. The holder 35^a and plate 39 have flat upper and lower walls 38^a and 39^a different in length or otherwise and the opening 43 in the casing occupied by the unit is intimately fitted by it so that the unit can only be inserted in one position, namely the correct position. Spacers 44 of arcuate form separate disks 34. Also an end disk 45 is included in the disk assembly. Said spacers and disk 45 are non-rotatable since they have lugs 46 disposed in a longitudinal slot 47 of holder 35^a. Said disk 45 has a slot 48 which is entered by the key and has shoulders 49 to limit the turning movement thereof in both directions.

The said unit as shown in Figures 5 and 11 is removable as an entirety from the casing 10 so that a new unit may be substituted therefor or so that the disks 34 may be varied in order to alter the combination.

In order to removably hold the unit in place within the section 10, an opening is provided in that section as at 43 through which the unit is inserted and removed. When in place within the section 10, the disk 36 overlaps the adjacent side wall of the casing, and fastening arms at 50, extend into the grooves 38, whereby the unit is held in place in the casing 10. The fastening arms 50 are pivoted at 51 to the section 10 and they are retained in the grooves after withdrawal of the key so that a blow or shock cannot disengage them as by means of a spring such as that shown at 52. A keyhole 53 is provided through the casing 10 so that a key 54 may be inserted, to engage adjacent ends 50^a of the fastening arms 50, so as to spread the fastening arms at their locking ends, thereby releasing the unit so that it may be removed. The key cannot be withdrawn until the arms are in the locked position in the grooves. Regardless of the spring 52, due to the shape of the arms, the latter are operated positively by the key. Step pins 51^a are provided to limit the movement of the arms 50. One of the arms 50 has a pin or projection 52^a thereon, whereby when the arms 50 are retracted by operation of key 54, the projection 52^a, as shown in Figure 1, engages the latch 31, thus retracting it, and removing the only part which interferes with the removal of the unit. It will be understood of course that when the key is inserted in groove 42 and acts on the disks 34, the edges at the slots 35, serve as cams, to elevate or displace the lug 32 of said latch 31.

It will also be apparent that when the bolt 16 is retracted, lug 32 on latch 31 will engage under the block 16^a. When in this position it is impossible to actuate arms 50 because of the engagement of projection 52^a with the latch 31. When, however, the bolt 16 is in advanced position, lug 32 is in position to avoid engaging the underside of block 16^a and the arms 50 may be moved to disengage their free ends from groove 38, and the unit may be removed and replaced. It follows that as the opening 43 for the unit is in the back plate of the lock casing, on the inner side of the door or other closure, the unit cannot be changed until the customer's key, fitting the unit, has been applied to open the door or other closure, and then advance the bolt to move arms 50 and that he has control of the operation of the lock while his keys are in his possession. Furthermore, as the projection 52^a holds the latch 31 in raised position when the arms 50 are disengaged from groove 38, and it is necessary that lug 32 engage in the alined slots 35 in disks 34 to actuate the bolt to retracted position to close the door, and cannot so engage while the latch is so engaged, it follows that the door cannot be closed until the unit is securely fastened in position on the lock casing by engagement of arms 50 therewith.

The cover 11 is preferably provided with

cylinders at 55 and 56 adapted to surround adjacent portions of the studs 41 and 26, respectively and they also have extensions of their bores at 57 and 58, which permit the bits of the different keys to gain access to the various parts.

Various changes may be resorted to provided they fall within the spirit and scope of the invention.

10 I claim as my invention:—

1. A lock of the class described comprising a casing, a removable key-controlled unit therefor removably carried by the lock, said unit having grooves in its outer face, fastening elements engaging said grooves to prevent accidental displacement of said unit, and key operable means to simultaneously actuate said elements, the engagement of said fastening elements and the key preventing withdrawal of the key when the elements are disengaged from the grooves.

2. A lock of the class described comprising a casing, locking means carried thereby, a unit comprising a holder removably inserted into said casing, said holder having grooves, locking arms on the casing engaging said grooves to prevent accidental detachment of the holder, permutation disks carried by the holder, a spindle carried by the holder and associated with the disks, said spindle having a key slot whereby a key may be inserted to engage the disks.

3. A lock of the class described comprising a casing, locking means carried thereby, a unit comprising a holder removably inserted into said casing, said holder having grooves, locking arms on the casing engaging said grooves to prevent accidental detachment of the holder, permutation disks carried by the holder, a spindle carried by the holder and associated with the disks, said spindle having a key slot whereby a key may be inserted to engage the disks, and an end plate on the holder.

4. A lock of the class described having a key operated permutation mechanism including a holder, a spindle, permutation disks in the holder rotatable about the spindle, spacers between the disks, an end disk on the spindle to limit movement of the key, said holder having slots and said spacers and end disk having lugs disposed in said slot.

5. A lock of the class described, comprising a casing, a cylinder on a wall of the casing and communicating with its interior the opposite wall of the casing having an opening in alignment with said cylinder, a unit insertable through said opening and engaging in said cylinder, said unit containing key controlled means necessary for operation prior to operating the lock, and means to hold said unit in the casing, said means being controllable through the wall of the casing through which the unit is insertable.

6. A lock of the class described, comprising a casing, a cylinder on the front wall of the

casing and communicating with its interior, the rear wall of the casing having an opening axially aligned with said cylinder, a unit insertable through said opening and engaging in said cylinder, said unit containing key controlled means necessary for operation prior to operation of the lock and provided with a groove in the outer face of its side wall, arms pivotally engaging in said casing and adapted to engage said groove to hold the unit in the casing, extensions on said arms, and key operable means to engage said extensions to move said arms from engagement with the groove.

7. A lock of the class described, comprising a casing, a removable key controlled unit insertable through aligned openings in the casing and having a groove in the outer face of its side wall, fastening elements adapted to engage in said groove and hold the unit in the casing, and key operable means to simultaneously actuate said elements, the engagement of said fastening elements and the key preventing withdrawal of the key when the elements are disengaged from the groove.

In testimony whereof I affix my signature.

JOHN A. KATZ.
